UNITED STATES PATENT OFFICE.

BENJAMIN W. TUCKER, OF SOUTH ORANGE, NEW JERSEY, ASSIGNOR TO CORONA TYPE-WRITER COMPANY, INC., A CORPORATION OF NEW YORK.

TYPE-WRITING MACHINE.

1,279,046.

Specification of Letters Patent. Patented Sept. 17, 1918.

Application filed May 1, 1916. Serial No. 94,661.

To all whom it may concern:

Be it known that I, BENJAMIN W. TUCKER, a citizen of the United States, and a resident of South Orange, county of Essex, 5 and State of New Jersey, have invented certain new and useful Improvements in Type-Writing Machines, of which the following is a full, clear, and exact description.

This invention relates more particularly 10 to a front strike or other visible writing machine wherein one part of the machine is movable relatively to another part to make the machine compact when not in use and to adapt the same for convenient transportation.

One of the principal objects of the invention is to provide a collapsible type-writing machine having a main frame part adapted to support the type-bar action including the type-bars and the key-operated levers therefor, and another relatively and horizontally movable frame part on which is mounted the platen and carriage and the associated parts usually coöperating with the platen, and so to construct said frame parts that one of the frame parts may be moved from a normal operative position to a more compact one.

Another object of the invention is to provide a simple and efficient horizontally collapsible writing machine in which there is a complete break between the associated parts for the platen carriage including the universal bar and the type action.

Other objects of the invention are to provide simple and efficient means for holding the frame parts of the machine and for locking the same in a normal position or in an abnormal inoperative position; to provide 40 simple means whereby the universal bar is adapted to be moved to a compact position with the platen carriage and in the normal operative position of the said bar adapted to be engaged by and moved during the printing movement of the type-bars; and to provide simple means whereby a carriage and the associated parts including the universal bar may be suitably mounted upon a horizontally slidably held frame part of the main machine frame.

A further object of the invention is to provide a simple and efficient machine wherein the frame parts are adapted to have a compact movement and said frame parts so con-

structed that either a type segment or platen 65 case shift may be employed.

A still further object of the invention is to provide a machine wherein the parts may be readily constructed and assembled.

With these and other objects in view, the 60 invention will be hereinafter more particularly described with reference to the accompanying drawings, which form a part of this application, and will then be pointed out in the claims at the end of the description.

In the drawings, Figure 1 is a plan view, partly broken away, of one form of machine embodying the invention, showing the parts in their normal operative position. 70

Fig. 2 is a longitudinal section from front to rear of the machine showing the type action and the platen carriage with the associated parts in normal operative position, the section being taken on the line II—II 75 of Fig. 1.

Fig. 3 is a side elevation, showing the parts of the frame with the parts mounted thereon moved to a compact and inoperative position.

Fig. 4 is a front elevation.

Fig. 5 is a longitudinal section showing a form of platen shift mechanism that may be employed instead of the type segment shift shown in the other figures.

Fig. 6 is a fragmentary sectional plan of the shift mechanism shown in Fig. 5; and

Fig. 7 is a longitudinal section showing the type action with one of the type bars forced to printing position.

While the invention is applied to a particular kind of typewriting machine, it will be understood that the invention and many of the features shown and described may be employed in connection with various kinds 90 and constructions of writing machines.

In Figs. 1 to 4 the invention is shown as applied to a machine wherein the type-bars operate the universal bar and wherein the type-bars are shifted for case shift purposes. As shown the main frame 10 comprises a main frame part 11, forming the base for the machine, and a relatively movable frame part 12. The base or frame part 11 comprises side plates 13 which may be 100 connected at their front portions by a transversely substantially L-shaped bar 14, and said base or frame part may be provided

with means for holding the usual rubber feet or tips 15 to support the machine. A transversely extending bar 16 extends between the sides 13, and pivotally held in slots 17 in said transversely extending bar are levers 18 and 19. These levers are arranged in pairs and are pivoted intermediate their ends to rods 20 which are held to the bar 16, and at their forward ends said levers 10 are pivotally held to parts 20^a of the levers 21. On the upper ends of the levers 21 are keys 22 by which the levers are operated. The upper ends of the levers extend in different directions so as to provide a plurality 15 of banks or groups, the keys 22 of the different banks being at different elevations as is usual in the keyboards of typewriting machines. Each key-lever 21 has its operating pair of levers 18 and 19 and said 20 levers at the inner ends are connected in pairs by a link 23. A rod or link 24 connects each link 23 and pair of levers 18 and 19 to an arm 24^a of a type-bar 25, there being a spring 25^a tending normally to hold 25 each key-lever in its normal position. The type-bars are pivoted at 26 to a vertically movable segment 27 at their rear ends and at their forward ends are provided with a plurality of type 28 varying in number according to whether a single or double case 30 shift is employed. If a single case shift is employed each type-bar carries two types or characters and if a double case shift is employed three type characters are arranged 35 at the forward end of each type-bar. As the keys 22 are depressed, the levers 18 and 19 will be moved on their pivots and through the links 23 and 24 will move the type bars on their pivots to force the type thereon 40 upwardly and rearwardly to make an impression on the work sheet about a platen 29 the latter being mounted on a carriage 30 which is adapted to travel transversely of the machine on the main frame part 12. 45 The main frame part 12 may comprise side plates or members 31 which may be connected at their rear portions by a transversely extending bar 32. This bar is adapted to form a bed for the carriage 30 50 along which bed said carriage is adapted to travel. The frame part 12 has its side plates 31 held to slide horizontally on off-set portions 33 of the side plates 13 of the main base member 11. The off-set portions 33, 55 each have a substantially horizontal straight part 34 on which rests the straight lower edge 35 of the frame side plates 31, and each of the frame side plates 31 bears against and is adapted to slide along a vertically 60 extending part 36 of the base side plates 13. In each part 36 is a horizontally extending slot 37, Fig. 3, through which is adapted to extend the shank or stem of a screw 38. Each screw has a milled head 39 by which 65 the same may be easily rotated and at its inner end each screw is adapted to engage a threaded opening in one of the sides 31 of the main frame part 12. The screws 38 each have a clamping collar or shoulder 40, and when the said screws are released the 70 frame part or member 12 with the parts mounted thereon may be forced forwardly from the position shown in Fig. 2, to that shown in Fig. 3 or vice versa, and by tightening the screws the frame parts may be held 75 in such adjusted positions. In the position shown in Fig. 2, the parts are in their normal operative position while in Fig. 3 the frame parts have been moved so that the machine is materially shortened from front 80 to rear making the machine more compact and convenient for transportation purposes. 85 As a case shift various means may be employed. As shown the type-bar segment 27 is held to a frame 41 and this frame is mounted upon parallel arms 42 and 43. The arms 43 are pivotally held to the frame sides 13 while the arms 42 are held to a transversely extending shaft 44. One of the arms 42 forms a part of a bell-crank 90 lever 45, the upwardly extending arm 46 of which is provided with a roll 47. The roll 47 extends into slots 48 and 49 of shift levers 50 and 51 respectively. The slots 48 and 49 extend in opposite directions so that 95 when one shift lever is depressed it will move the segment 27 and frame 41 vertically in one direction, and when the other lever is depressed it will move said segment in the opposite direction. The shift levers extend 100 forward and are provided with keys 52 on their outer ends and are pivoted to bosses or extensions 53, Fig. 4, projecting inwardly from one of the sides 13 of the base or frame part 11. The normal position of the segment 27 is such as to place the intermediate type of the type-bar in a position for making an impression on the work sheet when the key-levers are depressed. If the shift 105 lever 50 for example is depressed the slot 110 48 thereof will cause the roll 47 to be moved inwardly and this will force the segment 27 downwardly, while if the shift lever 51 is depressed the roll 47 will be forced forwardly and this will elevate the arms 42 115 thereby elevating the segment 27 and the frame 41 on which the segment is mounted. This frame 41 has forwardly extending arms to which the type basket 54 is held so that 120 said type basket, type-bars and type segment may all move together vertically as the shift levers 50 and 51 are depressed. The slots 48 and 49 of the shift levers intersect and are so arranged that they substantially lock the roll 47 in its normal position until 125 one of the shift levers is operated. The shift levers may be restored to their normal position by means of springs 55 and the type basket and segment may be counterbalanced or assisted in being held in its normal posi- 130

tion by means of one or more springs 56. The arrangement and construction of the type action and shift mechanism is not new with applicant and is not specifically claimed herein.

The platen carriage and the associated parts for the most part are substantially the same as embodied in the Corona typewriter. As shown the platen 29 is mounted to rotate 10 at its ends in the carriage 30 and is provided at one end with a knob 57 and at its other end with suitable line-spacing mechanism by which the platen may be rotated in the usual way. The paper apron 58 has a pressure 15 roll 59 and a scale 60 mounted thereon, and movable with the carriage are paper fingers 61 which are adjustable lengthwise of the platen. The carriage base 62 may have rolls 63 and a track 64 under which are suitable anti-friction devices, as balls, by which 20 the carriage may move easily along the bed 32 under the tension of the usual spring drum in the usual way.

A universal bar 65 is mounted to reciprocate horizontally under the carriage bed 32. This universal bar extends transversely of the machine between the side plates 31 of the main frame part 12 and said bar has a downwardly extending flange 65* which is 25 adapted to be engaged by a part 66 on each of the type-bars 25. The universal bar at its ends has angular parts 67 provided with lugs to which are pivoted the upper ends of arms 68. These arms 68 are pivoted at 69 30 at their lower ends to the side plate 31 and are adapted to support the universal bar so as to move horizontally when actuated by any one of the type-bars. The universal bar may be provided with a tappet as 70, Fig. 1, 40 which tappet is adapted to engage a part 71 extending inwardly from a dog carrier forming a part of an escapement mechanism. The escapement mechanism and dog carrier is not shown in detail but is substantially the same and is operated in the same 45 way as in the Corona typewriting machine.

It will be evident that when the keys 22 are depressed to operate the type-bars for printing purposes the type-bars during their 50 upwardly and rearward movement will engage and move the universal bar and such movement of the universal bar will move the escapement dogs thereby permitting the carriage to move a letter space under the 55 control of the spring drum or other tension mechanism.

The universal bar may serve as a means on which may be mounted a part of the mechanism for feeding the ribbon lengthwise as well as the means whereby the ribbon may be vibrated to cover and uncover the printing point. The specific construction of such features are neither shown in detail nor are they claimed specifically in 60 this application and have a bearing in this 65

application only so far as their mounting and arrangement in relation to other parts of the machine are concerned. The universal bar for the ribbon lengthwise feed mechanism carries a pawl 72 on each side thereof 70 and each pawl is adapted to engage a toothed wheel 73. The toothed wheel 73 carries a worm 73* and this worm is adapted to engage a worm wheel 74 on the shaft of each of the spools 75. The spools 75 are to be held to rotate with a shaft by means of a nut 76 as in the Corona typewriter so that on releasing one nut and tightening the other the ribbon may be fed to either side of the machine with a step-by-step movement, 80 such movement being effected by the engagement of the pawls 72 with the wheels 73 during the reciprocatory back and forth movements of the universal bar at each printing operation.

The universal bar may be also operated by the space bar 77 which may be operatively connected to a spacing lever, not shown, in substantially the same manner as the connection is made between the key-operated levers and the type-bars, a spring 77* being provided to restore the space-bar to its normal position. The spacing lever for operating the universal bar without printing may be exactly the same as the 95 type-bar only of less length and may normally lie in close relation to one of the type-bars so that on the depression of the space bar the spacing lever will be forced upwardly and rearward and thereby actuate 100 the universal bar to trip the escapement and permit letter-spacing.

In the construction of the machine shown and described the main frame comprises substantially two parts adapted to move relatively to each other and horizontally. The platen carriage and its associated parts together with the universal bar is mounted upon one of said frame parts and the type action as well as the means for operating 105 the universal bar for spacing purposes are mounted upon the other of the main frame parts. There is a complete break between the associated parts of the platen carriage and the type action and the construction 110 is such that the platen carriage with the associate parts may be moved forwardly so as to be spaced substantially over the type-bars and in a compact and inoperative position.

Figs. 5 to 7 show a construction somewhat similar to that shown in Figs. 1 to 4, except that the parts are arranged and constructed for a platen shift instead of a type segment shift. In this form of machine the base or frame part 78 of the main frame comprises side plates 79, a forward plate or bar 80 and a rear plate or bar 81. The upper portion of the member 78 is cut away and vertically movable thereon is a frame

part 82. The main frame part 82 comprises parts 83 and 84 which are relatively movable with respect to each other and with respect to the base or main frame part 78, the sides of the part of being connected together by the carriage bed 84^a. The part 84 at each side of the machine has a downwardly extending portion 85 and connected to said portion 85 at each side of the machine are parallel arranged arms 86 and 87. The arms 86 at opposite sides of the machine are pivoted to the side plates 79 on the base member and the arms 87 are held to a transversely extending shaft 88. One 15 of the arms 87 has an upwardly extending arm 89 forming a bell-crank and at the upper end thereof is provided with a roll 90. The roll 90 is adapted to enter slots 91 and 92 of shift levers 93 and 94 respectively. 20 The shift levers 93 and 94 at their outer ends are provided with keys 95 and are held in their normal position by means of springs 96 one end of each of which springs is held to one of the base side plates 79 and the other 25 end to an extension, as 97, on each of said levers. The shift levers are arranged in close relation on one side of the machine and at the rear ends are pivoted at 98 to an inwardly extending portion 98^a on the 30 base side plate 79. The slots 91 and 92 of the shift levers are substantially L-shaped in form and the upper or roll actuating portion 91 is inclined to a less extent than the same portion of the slot 92 so that on the 35 depression of the lever 93 the roll 90 will be moved to a less extent than on the actuation of the lever 94. The substantially horizontal portion of each of the slots 91 and 92 is for the purpose of permitting the shift 40 levers to be moved independently and if it were not for such horizontal portion of the slot the roll could not move forward and in that case the frame part 84 could not be raised. The part 84 is supported by the 45 arms 86 and 87 in substantially the same manner as the type-bar segment of the other figures, but in this case the normal position of the support 84 is that shown in Fig. 7 and the two case shift movements are upwardly instead of one shift movement being upwardly and the other downwardly as in the case with the construction shown in Figs. 1 to 4.

The frame part 83 is slidably held to 50 move horizontally on off-set portions 99 and such off-set portions are in alinement with off-set parts 100 of the side plates 79 of the main frame part 78. Each off-set part 99 is slotted, and passing through each slot 101 is a stem of a screw 102. Each screw 102 is provided with a milled or other head 103 by which the screw may be rotated and said screws 103 of opposite sides of the machine are adapted to hold the members 83 and 84 55 in either the normal operative position

shown in the drawings or in the compact position when said parts 83 and 84 are moved relatively to adapt the parts 83 to be moved forward in substantially the same manner as the frame part 12 is moved in 70 the other figures. The parts 83 and 84 may be suitably guided on the frame part 78, and the parts 85 may bear against the base side plates 79 to steady the parts and hold them in alinement. On the part 83 is 75 mounted a platen carriage 104 and in this carriage is a platen 105 about which the work sheet may be passed as usual.

The type action, except that the type-bars are not shifted is substantially the same as 80 that already described and the associated parts for the platen are also similarly constructed, the main difference being that the main frame has two parts, one of which is itself divided in two parts to adapt the 85 platen to be elevated for case shift purposes. It will be understood that my invention is not limited to a carriage supporting frame part having a purely horizontal movement, as it will be obvious that 90 the guiding means for said frame part may be inclined, if desired, in order that the carriage and associated parts may have a downward and forward movement while upright instead of a strictly horizontal movement. 95

Having thus described my invention, I claim as new and desire to secure by Letters Patent:—

1. In a typewriting machine, the combination of a base frame part, an upwardly movable frame part supported on the base frame part, a platen carriage movable from a normal operative position at the rear of the base frame part to a more compact inoperative position above the base frame 10 part, a movable support for the platen carriage, connections between said carriage support and said upwardly movable frame part whereby said support may be moved forwardly and rearwardly while upright 110 to move the carriage to and from compact position, a key action, type bars, and case shift mechanism for actuating said upwardly movable frame part to impart a case shift movement to the platen carriage. 115

2. In a typewriting machine, the combination of a base frame part having side members formed with laterally offset portions forming guide-ways, a platen carriage, a carriage-supporting frame part 120 slidably supported on the guide-ways formed by the offset portions of the base and movable from a normal operative position forwardly to a more compact position.

3. In a typewriting machine, the combination of a base frame part having side members formed with substantially horizontal laterally extending portions forming 125 ways, a frame part slidably supported on said ways and movable from an operative 130

rearwardly extended position forwardly to a more compact position within the base frame part, a keyboard and printing instrumentalities supported on the base frame part, and a platen carriage, ribbon mechanism, and escapement mechanism, all supported on the movable frame part.

4. In a typewriting machine, the combination with printing instrumentalities, a 10 platen, and a platen carriage, of a support for said carriage adapted to hold the platen in operative relation to said printing instrumentalities, said support being movable forwardly and substantially horizontally 15 with the carriage in an upright position thereon to place the carriage and platen in a more compact inoperative relation to the printing instrumentalities, and means for imparting a case shift movement to the 20 platen carriage.

5. In a typewriting machine, the combination of a base frame part, a keyboard and type action supported on said base, a 25 platen carriage, a slidably held support for the carriage movable forwardly to place the carriage in compact relation to the keyboard when the machine is not in use, and means for imparting a case shift movement to the platen carriage.

6. In a typewriting machine, the combination of a base frame part, a keyboard and type action mounted thereon, a platen carriage, and support for the platen carriage movable substantially horizontally relatively 35 to the base to move the carriage, while upright, from its normal operative position forwardly to a more compact position when the machine is not in use, and means for moving said support vertically relatively 40 to the base to impart a case shift movement to the platen carriage.

7. In a typewriting machine, the combination of a three-part main frame comprising a stationary base frame part, a vertically movable frame part, and a slidably mounted frame part movable forwardly relatively to the base frame part from an extended normal operative position to a compact inoperative position when the machine 50 is not in use.

8. In a typewriting machine, the combination of a three-part main frame comprising a base frame part, a vertically movable frame part supported thereon, and a frame 55 part supported on said vertically movable frame part and movable forwardly relatively to said vertically movable frame part and said base frame part from an extended operative position to a compact inoperative 60 position to decrease the length of the machine.

9. In a typewriting machine, the combination of a three-part main frame comprising a base frame part, a vertically movable 65 frame part mounted thereon, and a frame

part slidably held to said vertically movable frame part and movable forwardly relatively to said base frame part and vertically movable frame part from a normal operative position to a compact position to decrease the length of the machine when the machine is not in use. 70

10. In a typewriting machine, the combination of a main frame comprising a base frame part and a frame part having a vertical movement and a substantially horizontal forward and rearward movement relatively to the base frame part, a platen carriage supported on said movable frame part and movable therewith while upright from a normal operative position forwardly to a more compact position, a key-action mounted on the base frame part, type bars mounted on the base frame part, and case shift means mounted on the base frame part for 80 imparting a vertical movement to said movable frame part. 85

11. In a typewriting machine, the combination of a main frame comprising a base frame part and a frame part having a vertical movement and a substantially horizontal forward and rearward movement relatively to the base frame part, a platen carriage supported on said movable frame part and movable therewith while upright from a normal operative position forwardly to a more compact position, ribbon mechanism supported on the movable frame part, escapement mechanism supported on the movable frame part, a key-action mounted on the base 95 frame part, type bars mounted on the base frame part, and case shift means mounted on the base frame part for imparting a vertical movement to said movable frame part. 100

12. In a typewriting machine, the combination of a main frame comprising a base frame part and a frame part having a vertical movement and a substantially horizontal forward and rearward movement relatively 110 to the base frame part, a platen carriage supported on said movable frame part and movable therewith while upright from a normal operative position forwardly to a more compact position, ribbon mechanism supported on the movable frame part, escapement mechanism supported on the movable frame part, a universal bar supported on the movable frame part, a key-action mounted on the base frame part, type bars 115 mounted on the base frame part, and case shift means mounted on the base frame part for imparting a vertical movement to said movable frame part. 120

13. In a typewriting machine, the combination of a base frame part, a vertically movable frame part supported thereon, a frame part supported on said vertically movable frame part and movable forwardly relatively thereto in a substantially horizontal 130

- plane from a normal extended operative position at the rear thereof to a more compact position over the base frame part, a platen carriage supported on said forwardly movable frame part, a key-action, type bars, and case shift mechanism for actuating said vertically movable frame part.
14. In a typewriting machine, the combination of a base frame part, a vertically movable frame part mounted thereon, a frame part slidably held to said vertically movable frame part to move forwardly and rearwardly relatively thereto, a platen carriage mounted on said slidably held frame part and movable from an extended operative position to a more compact position over the base frame part, and case shift mechanism for actuating said vertically movable frame part.
15. In a typewriting machine, the combination of a base frame part, a vertically movable frame part mounted thereon, a frame part slidably held to said vertically movable frame part to move forwardly and rearwardly relatively thereto, a platen carriage mounted on said slidably held frame part and movable from an extended operative position to a more compact position over the base frame part, case shift mechanism for actuating said vertically movable frame part, type bars mounted on the base frame part, and keys mounted on the base frame part and operatively connected with the type bars.
16. In a typewriting machine, the combination of a base frame part, a vertically movable frame part mounted thereon, a frame part slidably held to said vertically movable frame part to move forwardly and rearwardly relatively thereto, a platen carriage mounted on said slidably held frame part and movable from an extended operative position to a more compact position over the base frame part, case shift mechanism for actuating said vertically movable frame part, type bars mounted on the base frame part, and keys mounted on the base frame part and operatively connected with the type bars, ribbon mechanism mounted on the slidably held frame part, escapement mechanism mounted on the slidably held frame part, and a universal bar mounted on the slidably held frame part and adapted to be actuated by the type bars.
17. In a typewriting machine, the combination of a stationary base, printing instrumentalities mounted thereon, a collapsible carriage-supporting frame comprising parts supported to move vertically in unison, one of said parts being movable relatively to the other forwardly and rearwardly, a platen carriage supported at the rear of said forwardly and rearwardly movable frame part and movable therewith while upright from an extended operative position at the rear of said base to a more compact inoperative position above said base, and case shift mechanism for imparting a vertical movement to said collapsible carriage-supporting frame.
18. In a typewriting machine, the combination of a frame, upwardly and rearwardly movable type-bars mounted therein, a key-action for actuating the type bars, a platen arranged in rear of and above the pivotal points of said type bars, means for supporting the platen to slide forwardly to an inoperative position over the type bars, and means for imparting a case shift movement to the platen.
19. In a typewriting machine, the combination of a frame, printing instrumentalities mounted thereon, a platen, a platen carriage, a support for the platen carriage, slidably mounted to move with the carriage in an upright position thereon forwardly of the frame to place the platen and carriage in compact inoperative relation with the printing instrumentalities, and mechanism for imparting a vertical case-shift movement to the platen carriage-support.
20. In a writing machine, the combination of supporting means, a key-board and a platen carriage mounted on said supporting means, means whereby said keyboard and carriage may be moved horizontally into closer relation when not in use than when in a normal operative position, and means for imparting a case shift movement to the platen carriage.
21. In a typewriting machine, the combination of a support having relatively slideable parts adapted to move forwardly and rearwardly of the machine to shorten its length in the inoperative position thereof, a platen mounted on one part, a keyboard mounted on another part, said keyboard and platen being maintained in an upright position at all times, and means for imparting a vertical case shift movement to the platen.
- This specification signed this 27th day of April A. D. 1916.

BENJAMIN W. TUCKER.
